UNITED STATES PATENT OFFICE.

HENRY G. TIDEMANN, OF ST. LOUIS, MISSOURI, ASSIGNOR TO THE HEINE SAFETY BOILER COMPANY, OF SAME PLACE.

DESIGN FOR A FURNACE-TILE.

SPECIFICATION forming part of Design No. 33,427, dated October 23, 1900.

Application filed May 28, 1900. Serial No. 18,332. Term of patent 14 years.

To all whom it may concern:

Be it known that I, HENRY G. TIDEMANN, a citizen of the United States, residing at the city of St. Louis, State of Missouri, have invented and produced a certain new and original Design for Furnace-Tiles, of which the following is a full, clear, and exact description, such as will enable others skilled in the art to which it appertains to make, and use the same, reference being had to the accompanying drawing, forming part of this specification, in which—

The figure represents a furnace-tile configured according to my new and original design.

This invention relates to a new and original design for a furnace-tile, the essential characteristics of which are the recessed inner surface and lower curved outer face merging without substantially changing the general direction into a straight upper side face which inclines inward toward the flat top face.

In the accompanying drawing, A indicates the tile as an entirety, whose inner face is provided with a semicircular recess *a*. The outer 25 lower face of the tile is curved, as at *b*, the upper portion of this curved face gradually merging without substantially changing the general direction into the upper straight side face *c*, which inclines from its juncture with 30 the curved face *b* inward toward the flat top face *d*, which it joins, forming an obtuse corner or angle.

What I claim is—

The design for a furnace-tile substantially 35 as herein shown and described.

In testimony whereof I hereunto affix my signature, in the presence of two witnesses, this 24th day of May, 1900.

HENRY G. TIDEMANN.
